(57) **CLAIM**

The ornamental design for a hitch cover, as shown and described.

DESCRIPTION

FIG. 1 is a perspective view of the ornamental design for a hitch cover according to the invention.

FIG. 2 is a rear elevational view thereof.

FIG. 3 is a front elevational view thereof.

FIG. 4 is a left side elevational view thereof, with the right side view being a mirror image thereto.

FIG. 5 is a top plan view thereof; and,

FIG. 6 is a perspective view thereof, in a similar orientation, showing an intended use of the invention as a hitch cover.

The structures depicted by means of broken lines in the figures have been shown for illustrative purposes only and form no part of the claimed design.
